UNITED STATES PATENT OFFICE.

WALTER MAJUSICK, OF CLEVELAND, OHIO.

FLOOR-SCRUBBING MACHINE.

Application filed July 12, 1924. Serial No. 725,560.

To all whom it may concern:

Be it known that I, WALTER MAJUSICK, a citizen of the United States, residing at Cleveland, in the county of Cuyahoga and State of Ohio, have invented certain new and useful Improvements in Floor-Scrubbing Machines, of which the following is a specification.

This invention relates to improvements in floor scrubbing machines having for an object to provide a simply and compactly constructed mechanism which may be easily assembled and operated by comparatively inexperienced persons.

15 A further object is to provide a rotary scrubbing machine of this character wherein the brush is entirely housed so as to prevent splashing of water about the floor being scrubbed.

20 It is also an object to provide a rotary brush and a housing carrying a buffer, the outside diameter of which is greater than the width of the remaining portions of the mechanism, the result being that only the 25 rubber buffer will strike pieces of furniture and the wall during the operation of the machine.

It is likewise an object to provide a rotary scrubbing machine of this character wherein 30 the housing and rotary brush with their associated parts may be swung upwardly upon the handle portion so as to facilitate transferring the machine from place to place.

35 In order that the invention and its mode of operation may be readily understood by persons skilled in the art, I have in the accompanying illustrative drawings, and in the following detailed description based 40 thereon set out the preferred embodiment of the same.

Figure 1 is a top plan view of the machine, and

45 Figure 2 is a side elevation of the machine with parts broken away and in section.

Having more particular reference to the drawing throughout which similar characters of reference designate like parts this improved scrubbing machine may be stated as comprising a shell or housing 5 preferably constructed of sheet metal in the form of an inverted pan, this shell having a vertical shaft 6 upon the lower end of which is removably attached a circular rotatable brush

head 7, carrying the usual bristles 8 as shown in Figure 2. A substantially inverted U-shaped bracket 9 formed of sheet metal is riveted or otherwise secured to the upper surface of the shell or housing 5, and has an opening vertically aligned with the central opening in the housing 5 whereby to serve as a journal for the upper end portion of the vertical shaft 6. Carried by the shaft 6 above the bracket 9 and below or within the shell 5 is a pair of adjustable collars 10 by means of which the vertical movement of the brush is effected. It is obvious that the bristles 8 in time will wear down and through adjustment of the upper collar 10, the brush may be lowered a distance to permit efficient operation of the brush.

Keyed to the vertical shaft 6 is a pulley 75 11 or the like driven from a small electric motor 12, through a belt 13 as illustrated. This motor 12 is preferably mounted rearwardly of the shell 5 upon a horizontally disposed bracket 14 as shown in Figure 2 80 of the drawings.

Obviously rotation of the brush would ordinarily splash water upon furniture and the wall in the room and in order to prevent this I arrange about the lower end or edge of 85 the shell 5, a depending flexible rubber guard or shield 14', the upper edge of which terminates in an annular buffer 15 of considerable thickness, and designed to prevent scratching or otherwise marring pieces of 90 furniture with which the machine may possibly come in contact. A pair of rearwardly diverging metal arms 16 are riveted at their forward ends to the shell 5 as shown in the drawings, the rear ends of these arms being 95 bent and disposed in relative parallel relation and apertured to receive a transverse shaft 17. This shaft 17 mounts at each end a wheel 18 preferably having rubber tires thereon and designed to function with a 100 pair of small wheels 19 to support the aforementioned housing 5 and the rubber shield 14 as well as the motor 12 and its associated parts. The small wheels 19, are mounted upon the lower ends of depending brackets 105 or arms 20, whose upper ends are riveted or otherwise secured intermediate the ends of the rearwardly diverging arms 16.

As shown in Figure 1 of the drawings a pair of rearwardly converging arms 21 is 110 mounted upon the shaft 17 at points near the wheels 18 and connected to a handle

portion 22 at the outer end of which is a hand piece 23.

Between the aforementioned arms is disposed a water reservoir or tank 24 from which water is conveyed into the housing through a pipe or hose 25 as illustrated in Figure 2, the flow of water through this pipe being controlled by means of a valve 26.

By reference to Figure 1 of the accompanying drawings it will be seen that the length of the transverse shaft 17 is somewhat less than the diameter of the brush housing, or shell and consequently in operation of this mechanism the brush may be moved about the floor being scrubbed without danger of side swiping a piece of furniture or the wall during the scrubbing operation. It is also apparent that when the operator wishes to move the scrubbing machine from one place to another he may if he so desires lift the rod 27 and swing the housing or shell 5 and its associated parts upwardly out of engagement with the floor and retain these parts in such position through connecting the rod 27 with the eye bolt disposed near the hand piece 23.

Applicant is aware of the existence of certain scrubbing machines, but all of these are so constructed as to render their manufacture and general use prohibitive, whereas in this mechanism all unnecessary parts have been eliminated and the structure is quite simplified.

Certain changes in the minor details of construction may be resorted to and such of these changes as fall within the scope of the appended claims I consider within the spirit of my invention.

I claim:

1. A floor scrubbing machine comprising, a rotatable brush, a shell arranged above the brush and extending downwardly around the brush head, a shield depending from the periphery of the shell to a point adjacent the end of the brush, an annular buffer arranged at the juncture of the shell and shield, a vertical central shaft carried by the brush and extending upwardly through the shell and vertically movable therein, a motor arranged to rotate the shaft, a pair of rearwardly diverging arms carried by the shell, a shaft loosely journaled in the rear ends of said arms, supporting wheels carried by the shaft, a handle connected to the shaft, a water reservoir arranged between said arms and immediately above the wheel carrying shaft, means for conveying water from the reservoir to the rotatable brush, a pair of brackets depending from and rigidly connected to said arms, and wheels carried by said brackets for co-acting with the first named wheels to support the parts associated with the vertical shaft and rotatable brush.

In testimony whereof, I affix my signature.

WALTER MAJUSICK.

2. A floor scrubbing machine comprising, a rotatable brush, a shell arranged above the brush and extending downwardly around the brush head, a shield depending from the periphery of the shell to a point adjacent the end of the brush, an annular buffer arranged at the juncture of the shell and shield, a vertical central shaft carried by the brush and extending upwardly through the shell and vertically movable therein, a motor arranged to rotate the shaft, a pair of rearwardly diverging arms carried by the shell, a shaft loosely journaled in the rear ends of said arms, supporting wheels carried by the shaft, a handle member fixed to the shaft and extending rearwardly therefrom, a pair of depending brackets arranged intermediate the ends of said rearwardly diverging arms, wheels mounted at the lower ends of said brackets to co-act with the first named wheels in supporting the set of the parts associated with the brush and shaft, tank mounted between said supporting wheels and means for conducting fluid from the tank to said brush.

3. A floor scrubbing machine comprising, a rotatable brush, a shell arranged above the brush and extending downwardly around the brush head and having a central opening, a vertical shaft extending through said opening and detachably connected to the brush head, a bracket carried by the shell and serving to support the upper end of said shaft, adjustable collars carried by the shaft to permit of vertical adjustment of the brush and shaft, a motor mounted upon the shell and adapted to rotate the shaft and brush, a flexible rubber shield depending from the lower edge of the shell to a point adjacent the end of the brush, a buffer arranged at the juncture of the shell and shield, a pair of rearwardly diverging arms carried by the shell, a shaft journaled in the rear ends of said arms, supporting wheels carried by the shaft, a handle connected to the shaft, a water reservoir arranged between said arms and immediately above the wheel carrying shaft, means for conveying water from the reservoir to the rotatable brush, a pair of brackets depending from and rigidly connected to said arms, and wheels carried by said brackets for co-acting with the first named wheels to support the parts associated with the vertical shaft and rotatable brush.
